(57) **CLAIM**

The ornamental design for a portable display set, as shown and described.

DESCRIPTION

FIG. 1 is a perspective view of a portable display set shown with the portable display and protective cover together in accordance with the present invention;

FIG. 2 is a front view thereof;

FIG. 3 is a back view thereof;

FIG. 4 is a left view thereof;

FIG. 5 is a right view thereof;

FIG. 6 is a top view thereof;

FIG. 7 is a bottom view thereof;

FIG. 8 is a perspective view of the portable display set shown with the portable display and protective cover together in an open position;

FIG. 9 is a perspective view of the portable display of the portable display set, shown separately to show aspects of the design that are not visible when combined;

FIG. 10 is a front view thereof;

FIG. 11 is a back view thereof;

FIG. 12 is a left view thereof;

FIG. 13 is a right view thereof;

FIG. 14 is a top view thereof;

FIG. 15 is a bottom view thereof;

FIG. 16 is a perspective view of the protective cover of the portable display set, shown separately to show aspects of the design that are not visible when combined;

FIG. 17 is a front view thereof;

FIG. 18 is a back view thereof;

FIG. 19 is a left view thereof;

FIG. 20 is a right view thereof;

FIG. 21 is a top view thereof; and,

FIG. 22 is a bottom view thereof.

(Continued)

The broken lines in the drawings depict portions of the portable display set that form no part of the claimed design.
